UNITED STATES PATENT OFFICE.

HERMINE ENGELKE SAHER, OF LOS ANGELES, CALIFORNIA.

DESIGN FOR A SAFETY-PIN HOLDER.

Application filed September 26, 1928. Serial No. 28,283. Term of patent 7 years.

To all whom it may concern:

Be it known that I, HERMINE ENGELKE SAHER, a citizen of the United States, residing at Los Angeles, county of Los Angeles, State of California, have invented a new, original, and ornamental Design for Safety-Pin Holders, of which the following is a specification, reference being had to the accompanying drawing, forming part thereof.

Figure 1 is a front elevation of a safety pin holder, showing the new design.

Figure 2 is a rear elevation thereof, and Figure 3 is a side elevation.

I claim:

The ornamental design for a safety pin holder as shown.

HERMINE ENGELKE SAHER.
